UNITED STATES PATENT OFFICE.

CARL GUSTAF SWEBILIUS, OF NEW HAVEN, CONNECTICUT, ASSIGNOR TO THE MARLIN FIREARMS CORPORATION, OF NEW HAVEN, CONNECTICUT, A CORPORATION OF DELAWARE.

FIREARM.

Application filed April 4, 1922, Serial No. 549,412. Renewed November 17, 1925.

To all whom it may concern:

Be it known that I, CARL G. SWEBILIUS, a citizen of the United States of America, residing at New Haven, in the county of 5 New Haven and State of Connecticut, have invented certain new and useful Improvements in Firearms, of which the following is a full, clear, concise, and exact description.

10 This invention relates to firearms and pertains more especially to repeating guns of the so-called "pump action type" in which the breech mechanism is operated through the medium of a sliding action rod and a 15 forearm.

It is an object of the invention momentarily to prevent the opening of the breech of a firearm after the firing mechanism has been released.

20 Another object of the invention is a simple and efficient means for momentarily rendering inoperative the breech mechanism actuating means.

Another object is an improved means for 25 maintaining the breech bolt locking means in locking position.

Other objects and novel features of the invention will be apparent from the following specification and accompanying drawings, wherein Fig. 1 is a side elevation partially in section of the receiver of a gun embodying the invention, the elements being 30 in cocked position. Fig. 2 is a similar view immediately after the hammer has struck the 35 firing pin.

The receiver 10 has one side wall cut away to provide access to the breech of the barrel 11. Reciprocatively mounted in the receiver and adapted to close said slot is a 40 breech bolt 12 riding on shoulders on the walls of the receiver and having a tongue and groove connection with the top wall of the receiver. The lower portion of the breech bolt is recessed and a locking bolt 13 is pivotally mounted therein, said bolt being 45 adapted to engage the stop 14 to maintain the breech bolt in closed position. The bolt 13 is rocked on its pivot by the action rod (not shown) in the usual manner to lock 50 and unlock the breech bolt.

A firing pin 15 is reciprocatively mounted in the breech bolt 12 and is arranged above the pivot point of the locking lever, the upper side of which is grooved to receive the

firing pin. The intermediate portion of the 55 firing pin is of larger diameter than its forward portion and of less diameter than its rear portion, thus providing a shoulder 16 near its rear end and another shoulder 17 near its front end. Near the rear end of the firing pin is a vertical groove 18 and on the rear end of the locking bolt 13 is a lug 19 which is adapted, when the firing pin is in its forward position, to slide into said groove, the lug having a rear oblique surface. A slide or wedge 20 is reciprocatively mounted on the pin and slides in a groove in the bottom of the recess in the breech bolt and has a depending lug 21 through which extends the intermediate portion of the firing 60 pin. A collar 22 is provided on the front portion of the firing pin and engages the first shoulder on the pin. A spring 23 encircling the firing pin is interposed between 65 the collar 22 and the front wall of the recess in the breech bolt, said spring serving to normally maintain the firing pin in its rear position with its head projecting beyond the rear of the breech bolt. A second spring 24 encircling the firing pin and interposed between 70 the collar 22 and the lug 21 normally maintains the slide 19 with the lug 21 in contact with the shoulder 16. Depending from the rear portion of the slide 19 is a lug 25 and in the locking bolt 13 is a socket 26 adapted to receive said lug when the slide 19 is 75 in its normal position. A hammer 27 and a trigger 28 are provided, said hammer and trigger having interengaging means (not shown) for retaining the hammer in cocked 80 position until the trigger is pulled.

The operation of this gun is as follows: Starting with the parts in the positions shown in Fig. 1, the gun is cocked and ready 85 for firing. The breech bolt 12 is locked in closed position by the locking bolt 13 and the latter is prevented from being rocked on its pivot by a rearward pull on the action rod because of the fact that the lug 18 is 90 out of register with the groove 17 in the firing pin and upward movement of the locking bolt will engage the lug with the firing pin. However, if it is desired to unlock 95 the gun, the firing pin may be pressed in 100 manually to bring the groove 17 into register with the lug 18 and allow the rocking of the locking bolt 13 to disengage its rear end from the stop 14. To fire the gun, the trig- 105

ger 27 is pulled, releasing the hammer 26 which strikes the exposed end of the firing pin 15 causing its front end to strike the primer of a cartridge and explode it. The forward movement of the firing pin brings the groove 17 and lug 18 into register and the firing pin is maintained in its forward position by the pressure of the hammer against it. However, it is not possible to unlock the breech at the instant the groove and lug come into register because of the wedge 19. The forward movement of the firing pin is communicated to the wedge through the medium of the shoulder 16 and the lug 20. During the forward movement of the firing pin, the wedge acquires enough inertia to cause it to slide forward along the firing pin a sufficient distance to move the lug 24 out of register with the socket 25 in the locking bolt. The rocking of the locking bolt 13 is now prevented by virtue of the engagement of the lug 24 with the top of the bolt. The wedge is, however, quickly returned to its normal position under the influence of the spring 23 to bring the lug into register with the socket. With the elements in their present position the gun may be opened by pulling rearwardly on the action rod. This will cause the locking bolt to rock to disengage it from the shoulder 14, this rocking movement being possible since the lug 24 and socket 25 and the lug 18 and groove 17 are now in register. As the lug 18 enters the groove 17, its rear oblique surface engages the rear wall of the groove 17 and slightly retracts the firing pin against the pressure of the hammer 26. The firing pin is not, however, moved to its rearmost position by this operation and the firing pin is pressed forwardly against the lug 18 by the hammer. Further rearward movement of the action rod causes the bodily rearward movement of the breech bolt to open the breech and effect the ejection of the exploded cartridge and the reloading of the gun. These operations are accomplished in the well-known manner by the usual extractor, ejector and carrier, which, not being a part of this invention, are not disclosed in the drawings. The rearward movement of the hammer also brings the hammer again into position to be engaged by the trigger. The breech bolt is now returned to its closed position. The firing pin is relieved of the pressure of the hammer and the spring 22 forces the firing pin rearwardly against the lug 18 which prevents the firing pin from moving into rearmost position. The lug 18, however, positively maintains the firing pin in an inoperative position during the reciprocation of the breech bolt so that if the hammer is prematurely released during the loading of the gun, the firing pin cannot be driven against a cartridge until the gun is breeched. As the locking bolt drops down

in position to engage the stop 14, the lug 18 is withdrawn from the groove 17 and the firing pin is then moved to its rearmost position by the spring 22, thus moving the groove 17 out of register with the lug 18 to prevent rocking of the locking bolt 13. The gun is now again ready for firing.

The action of the wedge 19 is effective to prevent accident from a "hang fire" cartridge or the unlocking of the gun while the pressure from the explosion of the cartridge is exerted against the breech bolt. For, if the gunner is pulling back on the forearm at the instant the firing pin is actuated, the locking bolt will engage the lug 24 on the slide 19 which was moved into engaging position simultaneously with the operation of the firing pin; the clearance between the top of the locking bolt and the bottom of the lug 24 being sufficient to allow the forward movement of the lug before the locking bolt can be rocked. The slide is wedged between the locking lever and the breech bolt and the former cannot now be actuated. A release of the pressure on the action rod will allow the wedge to move to its normal position under the influence of the spring 23. The gun may now be opened.

It is, of course, understood that various modifications may be made in the structure of this gun without in any way departing from the spirit of the invention as expressed in the following claims.

What is claimed is:

1. In a firearm, a breech bolt, a locking bolt pivoted to said breech bolt, a firing pin mounted in said breech bolt, and a member reciprocatively mounted on said firing pin and adapted when in one position to prevent rocking of said locking bolt. 100
2. In a firearm, a breech bolt, a locking bolt pivoted to said breech bolt, a firing pin mounted in said breech bolt, a member reciprocatively mounted on said breech bolt and adapted when in one position to prevent rocking of said locking bolt, and resilient means engaging said member to normally retain it in inoperative position. 110
3. In a firearm, a breech bolt, a locking bolt pivoted to said breech bolt, a firing pin mounted in said breech bolt, and means on said firing pin for momentarily preventing rocking of the locking bolt after the firing of the firearm. 115
4. In a firearm, a breech bolt, a locking bolt pivoted to said breech bolt, a firing pin mounted in said breech bolt, a member reciprocatively mounted thereon and adapted in one position to prevent rocking of said locking bolt, and means on said firing pin to communicate to said member motion in one direction. 120
5. In a firearm, a breech bolt, a locking bolt pivoted to said breech bolt, a firing pin mounted in said breech bolt, a member recip- 125

- reciprocatively mounted on said firing pin and being adapted in one position to prevent rocking of said locking bolt, means on said firing pin to communicate to said member 5 motion in one direction, and resilient means to urge said member in the opposite direction.
6. In a firearm, a breech bolt, a locking bolt having a socket pivoted to said breech bolt, a firing pin mounted in said breech bolt, a member reciprocatively mounted on said firing pin, a lug on said member adapted to register with said socket when said member is in one position and to engage said locking bolt when in another position, and means on said firing pin to reciprocate said member.
7. In a firearm, a breech bolt, a locking bolt having a socket pivoted to said breech bolt, a firing pin mounted in said breech bolt, a member reciprocatively mounted on said firing pin, a lug on said member adapted to register with said socket when said member is in one position and to engage said locking bolt when in another position, resilient means to normally maintain said lug in register with said socket, and means on said firing pin to move said member out of normal position.
8. In a firearm, a breech bolt, a locking bolt having a socket pivoted to said breech bolt, a firing pin mounted in said breech bolt, a member reciprocatively mounted on said firing pin, a lug on said member adapted to register with said socket when said member is in one position and to engage said locking bolt when in another position, and means for reciprocating said member.
9. In a firearm, a breech bolt, a locking bolt having a socket pivoted to said breech bolt, a firing pin mounted in said breech bolt, a member reciprocatively mounted on said firing pin, a lug on said member adapted to register with said socket when said member is in one position and to engage said locking bolt when in another position, resilient means to normally maintain said lug in register with said socket, and positive means for moving said member out of normal position.
10. In a firearm, a breech bolt having a socket, a locking bolt having a recess pivotally mounted in said socket, a firing pin mounted in said breech bolt, a member reciprocatively mounted on said firing pin, a shoulder on said firing pin, a spring to normally maintain said member in engagement with said shoulder, a second spring to retract said firing pin and a lug on said member adapted to register with said recess when said member is in normal position but to engage said locking bolt when said member is out of normal position.
11. In a firearm, a breech bolt, a locking bolt pivoted thereto, a firing pin, a slidably mounted inertia member adapted in one position to prevent rotation of said locking bolt, resilient means for normally maintaining said inertia member in inoperative position, and means for moving said inertia member against the action of said spring.
12. In a firearm, a breech bolt, a locking bolt pivoted thereto, a firing pin, a slidably mounted inertia member adapted in one position to prevent rotation of said locking bolt, resilient means for normally maintaining said inertia member in inoperative position, and means on said firing pin for moving said inertia member against the action of said spring.
13. In a firearm, a breech bolt, a locking bolt pivoted thereto, a reciprocable inertia member capable in one position of preventing rotation of said locking bolt, and means for reciprocating said member upon the firing of said firearm.
14. In a firearm, a breech bolt, a locking bolt pivoted thereto, a reciprocable inertia member capable in one position of preventing rotation of said locking bolt, positive means for moving said member into operative position upon firing the firearm, and resilient means to return it to inoperative position.
15. In a firearm, a breech bolt, a locking bolt pivoted thereto, and reciprocable inertia means for momentarily preventing the rotation of said locking bolt after the firing of said firearm.

In witness whereof I hereunto sign my name this 18th day of March, 1922.

CARL GUSTAF SWEBILIUS.
